UNITED STATES PATENT OFFICE.

JOHN J. BRANAGAN, OF MCKEES ROCKS, PENNSYLVANIA.

RAILROAD-RAIL JOINT.

1,307,110.

Specification of Letters Patent. Patented June 17, 1919.

Application filed March 1, 1919. Serial No. 280,109.

To all whom it may concern:

Be it known that I, JOHN J. BRANAGAN, a citizen of the United States, and a resident of McKees Rocks, in the county of Allegheny and State of Pennsylvania, have invented a new and useful Improvement in Railroad-Rail Joints; and I do hereby declare the following to be a full, clear, and exact description thereof.

10 My invention relates to a rail joint, and has special reference to such joints for use in connection with metallic ties for railroads, railways, etc., such as is shown, described and claimed in my United States Letters. Patent No. 1,256,199 granted on 15 February 12, 1918, of which this invention is an improvement.

20 The object of my invention is to provide a cheap, simple and efficient rail joint which will eliminate the use of spikes and bolts so commonly employed with the ordinary forms of rail road joints, and one which will allow the rails to expand and contract in case of changes in atmospheric temperatures.

25 Another object of my invention is to provide a rail joint which will stop the rails from spreading and creeping, as well as one in which the connecting parts for the rails will be completely covered up to prevent 30 the entrance of dirt, water and other foreign matter into the joint and thereby injure, rust and wear out the parts rapidly, and also one in which such connecting parts may be readily disassembled to allow for removal 35 and replacement of worn parts of the joints and rails.

40 To enable others skilled in the art to which my invention appertains to construct and use my improved rail joint and tie, I will describe the same more fully, referring to the accompanying drawing, in which:—

45 Figure 1 is a cross-section of a rail-road track, showing my improved joint applied thereto and with one side of the same in section;

Fig. 2 is a sectional view, taken on the line 2—2 Fig. 1 and looking in the direction of the arrows;

50 Fig. 3 is a cross section of the tie showing one side of the clamping bar with the rail removed;

Fig. 4 is a perspective view of one of the connecting keys; and

55 Fig. 5 is a like view showing the rails and connecting parts in position, with one side clamping bar removed.

Like symbols of reference herein indicate like parts in each of the figures of the drawing.

As illustrated in the drawing 1 represents 60 a metallic tie which is formed of cast metal and provided with a top plate 2 and side plates 3 to form a channel shape tie. A rail clamping bar 4 is formed adjacent each end of the top plate 2, and a rail clamping bar 65 5 is adapted to be removably placed on the said plate 2 and opposite each of the clamping bars 4 for clamping the rails *a* together as hereinafter described. The clamping bars 4 and 5 are each provided with a clamping 70 flange 6 for fitting under the head *b* and against the webs *c* of the rails *a* and such flange has a groove 7 formed on its inner face for receiving one side of the flanges *d* on said rails. The clamping bar 5 is slidably 75 mounted in a wedge-shaped seat 8 formed in the top plate 2 and is removably held therein in any suitable manner, such as by the compound wedge member 9, which engages with said bar and seat and with an abutment 10 80 formed on the top plate 2. A cover plate 11 having moving end flanges 11' fits over the wedge member 9, such flanges fitting against the ends of the wedge, clamping bar 5 and abutment 10 to hold the cover plate in place 85 and against longitudinal movement.

The tie 1 being of channel shape can also be provided with the cross-partitions 12 extending between the side plates 3 of the same, with the end partitions 13 acting as 90 end coverings for said tie, while a central longitudinal partition 12' can also be formed between said partitions 12 and 13, and such partitions 12, 13 and 12' will form pockets 14 in the tie and also act to suitably brace 95 the channel shape of such tie. The side plates 3 can also be formed of corrugated cast metal, as shown at 3' in Fig. 3, to strengthen the same, if desired.

Within each of the clamping flanges 6 on 100 the bars 4 and 5 are the two slots 15, which are formed on the inside or rail bearing faces of said flanges and are separated by the partition 16 which is adapted to bear against the webs *c* of the rails *a* and over 105 the opening or joint *e* between the adjoining rails. Connecting pins or keys 17 pass through slots or holes *f* in each of the rail webs *c*, and such pins are positioned in each one of the slots 15 of the bars 4 and 5. 110 These keys 17 are provided with integral heads 18 at one end of the same for bearing

2
against one side of the rail webs *c* and around the other end is placed a collar 19 which bears against the other side of such webs. A cotter pin 20 is placed through a hole in the end of the keys 17 for holding the collar 19 in place.

The manner of assembling and operation of my improved rail joint is as follows: The keys 17 are placed through the holes *f* in 10 the webs *c* of the adjoining rails *a* with the heads 18 on such keys on the one side of such webs for fitting within the slots 15 in the integral clamping bar 4 on the tie 1, and after such rails are in position, with their 15 flanges *d* fitting in the groove 7 in such bar, the collars 19 and pins 20 are put in position on the keys 17. The clamping bar 5 is then placed within the seat 8 in the tie 1 and slid to position, so that the keys 17 with such 20 collars 19 and pins 20 thereon will come within the slots 15 in said bar. The wedge member 9 can then be placed within the seat 8 and moved to place, so that in thus engaging with the abutment 10 and the bar 5, the 25 said bar and the bar 4 will be clamped against the rails 1, and all the parts will be thereby forced tightly together. A cover plate 11 can then be placed over the wedge member with its end flanges 11' abutting the 30 ends of said clamping bar 5 and abutment 10 and it can be locked in place by means of a post 21 on the wedge extending up into a cap 22 on the plate 11 where such post and cap are connected together by a pin 23 passing 35 through the same.

It will be evident that the rail joint can be easily and quickly disassembled for repairing or replacing broken parts by simply removing the pin 23 and unlocking and lifting up the cover 11, so that the wedge 9 can 40 then be moved along out of its seat 8 and the clamping bar 5 then taken out of said seat. This will enable the rails *a* to be removed 45 from the clamping bar 4 and then if desired the pins 17 can be taken out of the rails, by removing the pins 20 and collars 19 therefrom.

It will thus be seen that in the use of my improved rail joint all of the parts composing the same will be firmly and securely 50 clamped together, as well as completely locked in place, and thus prevent any possible separation or undue movement of the parts while in use.

If desired, the tie 1 can have its end and 55 intermediate pockets, or all of its pockets filled with concrete, while various other modifications and changes in the design and construction of my improved rail joint may 60 be resorted to without departing from the spirit of the invention, or sacrificing any of its advantages.

What I claim as my invention and desire 65 to secure by Letters Patent is:

1. In a rail joint, the combination with the

rails and a tie, of clamping bars on said tie for engaging with the rails and having slots within the same, keys having heads at one end for fitting within the slots in one bar and against the rails, and removable means 70 on the other end of said keys for fitting within the slots in the other bar.

2. In a rail joint, the combination with the rail and tie, of clamping bars on said tie for engaging with the rails and having 75 slots within the same, a partition in each of said slots for fitting over the joint between the rails, keys having heads at one end for fitting within the slots in one bar and against the rails, and removable means on the other 80 end of said keys for fitting within the slots in the other bar.

3. In a rail joint, the combination with the rails and tie, of clamping bars on said tie for engaging with the rails and having 85 slots within the same, keys having heads at one end for fitting within the slots in one bar and against the rails, and removable collars on the other end of said keys for fitting within slots in the other bar, said collars 90 being adapted to be held in place and against said rails by removable cotter pins passing through said keys.

4. In a rail joint, the combination with the rail and tie, of clamping bars on said tie for 95 engaging with the rails and having slots within the same, a partition in each of said slots for fitting over the joint between the rails, keys having heads at one end for fitting within the slots in one bar and against 100 the rails, and removable collars on the other end of said keys for fitting within the slots in the other bar, said collars being adapted to be held in place and against said rails by removable cotter pins passing through said 105 keys.

5. In a rail joint, the combination with the rails and a metallic tie, of an integral clamping bar adjacent one end of said tie for engaging with the rails, a removable clamping bar opposite said integral clamping bar for engaging with the rails, slots within said clamping bars, keys having heads at one end for fitting within the slots in said integral 115 clamping bar, and removable means on the other end of said keys for fitting within the slots in the removable clamping bar, said means being adapted to engage with said rails.

6. In a rail joint, the combination with 120 the rails and a metallic tie, of an integral clamping bar adjacent one end of said tie for engaging with the rails, a removable clamping bar opposite said integral clamping bar for engaging with the rails, slots within said 125 clamping bars, keys having heads at one end for fitting within the slot in said integral clamping bar, removable collars on the other end of said keys for fitting within the slot in the removable clamping bar, said collars 130

being adapted to be held in place and against said rails by removable cotter pins passing through said keys.

7. In a rail joint, the combination with the rails and a metallic tie, of an integral clamping bar adjacent one end of said tie for engaging with the rails, a removable clamping bar opposite said integral clamping bar for engaging with the rails, slots within said clamping bars, a partition in each of said slots for fitting over the joint between the rails, keys having heads at one end for fitting within the slots in said integral bar, and removable means on the other end of said keys for fitting within the slots in the removable bar, said means being adapted to engage with the rails.
8. In a rail joint, the combination with the rails and a metallic tie, of an integral clamping bar adjacent one end of said tie for engaging with the rails, a removable clamping bar opposite said integral clamping bar for engaging with the rails, slots within said clamping bars, partitions in said slots for fitting over the joint between the rails, keys having heads at one end for fitting within the slots in said integral bar, a removable collar on the other end of said keys for fitting within the slots in the removable bar, said collars being adapted to be held in place against the rails by removable cotter pins passing through said keys.
9. In a rail joint, the combination with the rails and tie, of a removable clamping bar for engaging with the rails, a removable

wedge member for fitting within a seat in the tie for engaging with said bar, a cover plate over said wedge member, and means for holding said cover plate in place.

10. In a rail joint, the combination with the rails and tie, of a removable clamping bar for engaging with the rails, a removable wedge member fitting within a seat in the tie for engaging with said bar, a cover plate over said wedge, and downwardly extending flanges on the ends of said plate for engaging with the ends of the wedge to hold said cover in place.

11. In a rail joint, the combination with the rails and tie, of a removable clamping bar for engaging with the rails, a removable wedge member fitting within a seat in the tie for engaging with said bar, a cover plate over said wedge member, and means for locking said cover in place.

12. In a rail joint, the combination with the rails and tie, of a removable clamping bar for engaging with the rails, a removable wedge member fitting within a seat in the tie for engaging with said bar, a cover plate over said wedge member, a cap on said plate, a post on said bar extending into said cap, and a pin passing through said post and cap to lock said cover in place.

In testimony whereof, I the said JOHN J. 65
BRANAGAN have hereunto set my hand.

JOHN J. BRANAGAN.
